PAN SUPPORT

George P. Flanagan, Springfield, Mass., assignor
to Oscar J. Seguin, Springfield, Mass.

Application April 7, 1933, Serial No. 665,017

1 Claim. (Cl. 248—30)

This invention relates to improvements in support for pans and the like.

The principal objects of the invention are directed to the provision of a device for supporting a pan or the like which consists essentially of a supporting frame to which are pivotally and slidably connected a plurality of supporting members so that the device may be made to suit various conditions and is adapted to assume collapsed and set up relations.

Where range oil burners are installed in a stove, range or the like, the upper side of the burner is disposed at a considerable distance below the lid opening in the stove so that the most efficient heating effect is not obtainable. According to the novel construction of the pan support of this invention, a pan or the like may be supported in the lid opening of a range or stove so that its lower side is in close proximity to the oil burner and thereby the best heating effects may be obtained.

The novel features of the invention which will hereinafter more fully appear reside in the provision of a supporting frame member, preferably in the form of a ring or the like which has pivoted and slidable therein a plurality of pan supporting members. This is so the device may be made to accommodate lid openings of various diameters and the supporting members thereof may be swung between collapsed and set-up positions while special means is provided to hold the supporting members in set-up position.

Various novel features and advantages of the invention will be hereinafter more fully referred to in connection with the accompanying description of the preferred form of the invention which is shown in the accompanying drawing, wherein:

Fig. 1 is a plan view of a device of the invention showing the novel features thereof.

Fig. 2 is an enlarged sectional view on the line 2—2 of Fig. 1.

Fig. 3 is a side elevational view of the device shown in Fig. 1.

Fig. 4 is a sectional view on the line 4—4 of Fig. 1.

Fig. 5 is an elevational view of an auxiliary supporting member which may be associated with the device shown in Fig. 1, and

Fig. 6 is a small scale inverted plan view of the device shown in Fig. 1 with the parts in collapsed relation.

Referring to the drawing more in detail the invention will be fully described.

The device includes a frame or main support

2, two or more supporting members 3 and a handle 6 as shown in Figs. 1 and 3.

The frame member 2 may be made in the form of a ring or it may take various forms. It is preferably made from a relatively thin strip of material which may have its ends joined together in any suitable manner. The handle 6 may also be of flat material with its inner end secured to the frame 2 in any suitable manner.

The supporting members 3 are preferably in the form of U's as shown and have cross members 4 and side members 8 which are bent upwardly therefrom. The extremities 10 of the sides are bent outwardly so as to pass through suitable openings provided in the ring 2. The members 3 and the openings in the ring receiving the parts 10 of said members are preferably so arranged that the members 4 are in a transverse relative position when the members are swung to the set up positions shown in Figs. 1, 2 and 3. These members 3 are preferably made from relatively spring-like wire.

The cross members 4 in their central part are provided with sockets such as shown at 12 in Fig. 2. These sockets are arranged for inter-engagement one with the other so that the members 3 are held in the set-up position shown in Figs. 1 and 2. In this position the members 4 are disposed so as to support a pan or the like which may extend downwardly within the ring 2.

When it is desired to collapse the members 3 to the position shown in Fig. 6 they are swung on their pivotal connections with the frame so that the parts 4 thereof may lie closely adjacent the frame one on top of the other. In this relation the pan support is relatively flat and thin to facilitate compactness and ease in shipping.

As stated the parts 10 of the supports are preferably slidable in the openings in the frame so that the device may be used in association with lid openings of different diameters. The parts 10 may slide relative to the frame whereby the parts 8 of the supports may move in and out and in that way the overall diameter of the side parts 8 of the members 3 are adjustable to suit conditions.

In use the device is set over the lid opening of a range or the like so that the members 3 extend therebelow carrying the cross members 4 disposed above the range burner. With an exceptionally large lid opening the parts 10 may be used to rest on the stove top around the opening and support the device. Otherwise the ring 2 may rest on the top of the stove around the opening.

In some cases it is desirable to provide a supple-

mental set of supports in association with the frame 2. For this purpose a pair of support members 20 as shown in Fig. 5 may be formed. These have a cross member 22 and upstanding sides 24 with outwardly extending parts 26. It will be noted that the side members 24 are of less length than the side members 8 of the members 3 previously described. Openings such as 28 in the ring may be provided for receiving the parts 26 of these support members 20 so that the members may be adjusted or moved between collapsed and set-up position.

With these supporting parts 20 in place in the frame the cross members 22 thereof are located above the cross members 4 of the members 3. When not desired for use the side members 24 may be moved inwardly to remove the parts 26 from their respective openings.

The parts may be made from various materials as may be desired in order to provide a strong rigid device adapted for the purpose of the invention. The form of the several component parts of the structure may be varied in accordance with the invention to adapt the device of the invention to various conditions.

Having described the invention in the form at present preferred what I desire to claim and

secure by Letters Patent of the United States is:

A pan holder of the class described comprising in combination, a relatively thin band of flat sheet metal formed to provide a closed ring member of a certain diameter provided with two pairs of diagonally opposite openings therethrough and having a handle member extending outwardly therefrom, and a pair of U-shaped supporting members of yieldable wire, each supporting member including a cross member of less length than said diameter of the ring member and side members extending from opposite ends thereof having their outer ends bent outwardly in opposite directions to provide retaining portions reciprocable and rotatable in opposite openings, said cross members being disposed at right angles to one another and having centrally disposed interfitting sockets all adapted and arranged whereby said supporting members may swing from a set-up position wherein their side members extend vertically at substantially right angles to said ring member with the sockets of their cross members interfitting to a collapsed position wherein their side members extend relatively horizontally adjacent the lower marginal edge of said band. 100
